COLLAPSIBLE CARTON

William H. Inman, Newark, N. Y., assignor to Bloomer Bros. Company, Newark, N. Y., a corporation of New York

Continuation of abandoned application Serial No. 238,931, July 27, 1951. This application August 16, 1955, Serial No. 528,611

12 Claims. (Cl. 229—39)

This invention relates to set-up, collapsible, cardboard cartons of the variety having bottom flaps so constructed as to be automatically unfolded and extended by erecting manipulation of the side walls, to conveniently distract the carton for filling with the desired contents. Cartons of this nature are commonly used to distribute food products, including frozen foods, and the carton walls tend to adhere to such contents, as ice cream, for example, so as to be difficult to separate and open without such damage to the carton as to make it unsuitable for further use. To avoid this difficulty, other cartons have been so constructed as to be not only easily opened, but with parts adapted to become disconnected from one another to more fully expose the contents, thus also rendering the carton unfit for further use. This application is a continuation of my copending application, Serial No. 238,931, filed July 27, 1951, Collapsible Carton, now abandoned.

One object of the present invention is to provide an improved carton of the general character described and so constructed as to be readily opened for access to the contents, but kept substantially intact and in condition for being closed again for further preservation of its remaining contents.

Another object is to supply a carton of this nature so constructed as to be readily manufactured and to be conveniently erected for filling, as well as convenient for use by the consumer as described above.

A further object is the provision of a carton constructed as described and capable of being readily opened by the consumer and conveniently closed again without soiling the fingers, for return to the refrigerator to preserve an unused portion of the contents.

Still a further object is to afford a carton having the above advantages in a form capable of being readily manufactured in quantity lots, by known machines and at relatively low cost.

To these and other ends the invention resides in certain improvements and combinations of parts, all as will be hereinafter more fully described, the novel features being pointed out in the claims at the end of the specification.

In the drawings:

Fig. 1 is a plan view of a cardboard blank for forming the carton;

Fig. 2 is a similar view with bottom flap portions folded over and glue applied;

Fig. 3 is an edge view of the blank as seen from the right in Fig. 2 but with outer wall portions partly folded over toward glued position;

Fig. 4 is a view similar to Fig. 3 but with the parts glued together and the carton in collapsed condition;

Figs. 5, 6 and 7 are top plan views of the inside of the carton in progressive positions of erection for filling;

Figs. 8, 9 and 10 are bottom plan views of the outside of the carton in progressive positions of erection for filling, corresponding to Figs. 5, 6 and 7;

2

Fig. 11 is a perspective view of the carton showing the same erected, filled and closed;

Fig. 12 is a similar view of the carton after being opened to remove a portion of the contents;

Fig. 13 is a fragmentary view similar to a portion of Fig. 2 but showing a modified construction; and

Fig. 14 is a view similar to Fig. 3 but showing the modified construction of Fig. 13.

The embodiment of the invention, herein disclosed by way of illustration, is preferably made with a one-piece cardboard blank such as shown in Fig. 1 of the drawings, cut and scored to form front, side, rear and closure walls 1, 2, 3 and 4, respectively, separated by parallel scored fold lines 5, 6 and 7, as shown. Closure wall 4 carries a securing strip 8 foldably connected therewith and adapted to be folded over and detachably glued to the free edge portion 9 of the opposite or front wall 1 when the walls are folded over, as hereafter described. Closure wall 4 also has its inner surface cut or otherwise scored along a line 10 to produce a weakened surface area 11, for a purpose hereafter described. Front wall 1 has a slit 12 extending inwardly from its free edge adjacent one end thereof, for a purpose hereafter described.

Walls 1 to 4, inclusive, are provided with top closure flaps 13 to 16, respectively, which are foldably connected therewith along a score line 17. Flap 13 is formed with a slit 18 cut therethrough and having its ends connected with score lines to facilitate the bending of the flap to open the slit 18 for the reception of a tongue or hook 19 on flap 15, for securing these top flaps in position for closing the top of the carton through which it is filled with the desired contents.

Front and rear walls 1 and 3 carry bottom closure flaps 20 and 21, respectively, foldably connected therewith along a score line 22. These flaps are provided with score lines 24 and 25, respectively, extending diagonally across and separating each of them into two sections, as 26 and 27, so that each may be folded on itself and folded over the side wall to which it is connected, as further described hereafter. Flap 20 carries a relatively narrow flange 28 foldably connected therewith along a score line 29.

The outer free edges of flaps 20 and 21 have the irregular shape shown in the drawings, including notches 32 and 33, respectively, for engagement with each other in the erected position, as hereinafter described. Side wall 2 has a substantially rectangular inner bottom flap 23 foldably connected therewith along a score line 30, between flaps 20 and 21 and flap 23 is crossed by a score line 31, as shown, to enable it to bend more flexibly while in contact with the front wall during the erection of the carton as hereinafter described.

In the folding and gluing of the blank, as shown in Fig. 2, flap 23 is folded over side wall 2. Bottom flap 20 is folded on itself and folded inwardly over walls 1 and 2 and its flange 28 is folded inwardly over the folded flap, as shown. Flap 21 is folded on itself and folded over wall 3. In this position of the parts glue is applied to a restricted area 34 of flap 21 and to the exposed side of flange 28 as shown at 35, a small portion 36 of the flange being preferably left unglued for engagement by a positioning part of a gluing machine. Glue is likewise applied in a narrow band 37 on securing strip 8, adjacent its line of fold, leaving an unglued outer edge portion 38 to provide a free full tab which is preferably extended as at 39 so as to be readily grasped.

In the further folding and gluing of the blank, the front and side walls 1 and 2, with the inwardly folded flaps 20 and 23, are folded over front wall 1 and closure wall 4, about the intermediate score line 6, as shown in Fig. 3, the flap 21 being folded inwardly as shown in Fig. 2. This brings the inner bottom flap 23 into glued cohesion with flap 21 and brings flange 28 of inwardly

folded flap 20 into glued cohesion with the area 11 of closure wall 4. Securing strip 8 of the underlying closure wall 4 is then folded upwardly around and over the outer or free edge 9 of the front wall and pressed down in glued cohesion therewith, thus completing the folding and gluing of the carton in the compact collapsed position shown in Fig. 4, ready for storage and shipment to the ice cream dispenser.

When it is desired to erect the carton for filling, this is quickly accomplished by inward pressure against the opposite folded edges, which serve to separate and distend the side walls in the progressive manner shown in Figs. 5, 6 and 7, as viewed from the open top of the container and in Figs. 8, 9 and 10 as seen from a bottom view. The separation of the rear wall 3 from the side wall 2 tends to pull the inwardly folded flap 21 and inner bottom flap 23 to erected position, while the separation of closure wall 4 and front wall 1 pulls inwardly folded flap 20 toward erected position. In such movement a portion of the edge of flap 20 rides under a portion of the edge of flap 21, while a portion of the edge of flap 21 rides under a portion of the edge of flap 20, with the result that the opposing edges move along one another in crossing relation and are finally interengaged in notches 32 and 33, as shown in Figs. 9 and 10. Such an engagement tends to limit the erecting movement with these inwardly folding flaps in a position normal to the walls of the carton and the erecting movement is further limited by the erecting movement of the inner bottom flap 23 and its engagement with the inside of flaps 20 and 21 along the bottom corners of the carton. The bottom flaps are quickly snapped to such erected position by merely pressing the opposite corners of the carton, as stated, leaving the top closure flaps 13 to 16, inclusive, in open position to receive the contents.

The carton, resting on its bottom, is then filled and top closure flaps 14 and 16 are folded down across the filling opening, in order, after which flap 13 is folded down, followed by flap 15, the tongue 19 of which is engaged in slit 18 of flap 13 to secure the closure of the top or filling opening. The terms "top" and "bottom" are herein employed in reference to the corresponding parts when the carton occupies this position for filling with its contents. It will be noted that tongue 19 is on the flap of the rear wall to which the closure wall is hinged and is pointed in the direction of the closure wall so that an opening pull on the latter serves to keep the tongue engaged in slit 18 and that end of the carton closed. The carton is then in condition shown in Fig. 11, for delivery to the consumer.

For opening the carton, the unglued free edge 38 of securing strip 8, and particularly its extension 39, is readily grasped and pulled to separate the securing strip from the front wall and the closure wall 4 from the flange 28. The surface area 11, weakened and limited by the score 10, pulls away from closure wall 4 and adheres to the flange so as to insure ready separation of the closure wall from the flange. Such detachment of the surface portion 11 terminates at the hinge line 7 of the closure wall, as indicated at 40 (Fig. 12) leaving a web of material connecting the flange with the top of the rear wall so as to maintain a connection between the front and rear walls and hold them in place and the bottom flaps in engagement. These provisions, together with the fact that the closure wall is glued only along the narrow bands 35 and 37, insure ready separation of the closure wall for raising it to open the carton.

The top closure flap 16, which does not contact the contents, is readily raised and the closure wall 4 is thus easily raised to the open position shown in Fig. 12. The remaining top closure flaps are maintained in closed position, so that the carton is maintained in shape while as much of the contents as desired is dipped out.

To close the carton again and preserve the residue of

the contents for future consumption, the closure wall 4 is folded down with its top flap 16 inserted between the top flaps 13 and 14 and with its securing strip inserted inside the top edge of the front wall. One end of the securing strip, however, is inserted through the slit 12 of the front wall so as to extend on the outside of the front wall in separated relation with the carton contents. This effectively closes the carton, ready for return to the refrigerator, while preserving a clean end on the securing strip extending to the outside of the front wall which may be grasped to raise the closure wall without soiling the fingers.

In a modified construction, the flange 28 may be formed at its inner end with a finger-like extension 41 (Fig. 13) to which glue may be applied along with the rest of the flange. In folding and gluing this construction, as the walls 1 and 2 are folded over (Fig. 14), the extension 41, with glue on its inner surface, is inserted in between the inner face of rear wall 3 and its inwardly folded flap 21 and so glued to the rear wall to take the place of the web connection 40 described above. The parts are then pressed down and completed in collapsed condition as shown for the first form of the invention. It is evident also that, in either form of the invention, the blank may be turned over, under side uppermost from the position shown in Figs. 1 and 2 and the parts scored, folded and glued in relatively reversed positions, as well understood in the art, the closure wall then opening in a right hand direction from the opposite side of the carton shown in Figs. 11 and 12.

The invention, as herein disclosed, comprises related embodiments of the invention originally disclosed in my prior patent application, Serial No. 238,932, now abandoned, which was copending with and filed on the same day as my prior patent application, Serial No. 238,931, now abandoned, of which the present application is a continuation. The inventions and embodiments originally disclosed in my application, Serial No. 238,932 were subsequently disclosed in a continuation application, Serial No. 352,160, now Patent No. 2,686,629, issued August 17, 1954. Certain features disclosed but not claimed herein are claimed in my above patent, No. 2,686,629.

It is apparent from the above description that the invention provides a carton which may be readily and economically manufactured from the usual materials and by known methods and standard machines, in compact collapsed condition for storage and shipment to the food dispenser. The latter may quickly erect the carton by merely pressing its opposite corners to erect its automatic bottom and then fill it and close its top in the usual manner, ready for delivery to the consumer. The consumer can easily open the carton to remove a portion of its contents by pulling on the pull tab 8 so as to raise the cover to open condition in which the contents may be readily dipped out to the extent desired. The carton may then be readily closed to preserve its remaining contents by closing and securing the cover as described, a portion of the pull tab being conveniently disposed on the outside of the front wall to provide means for further opening of the cover without soiling the fingers.

It will thus be seen that the invention accomplishes its objects and while it has been herein disclosed by reference to the details of preferred embodiments, it is to be understood that such disclosure is intended in an illustrative, rather than a limiting sense, as it is contemplated that various modifications in the construction and arrangement of the parts will readily occur to those skilled in the art, within the spirit of the invention and the scope of the appended claims.

I claim:

1. A collapsible carton having a self-erecting bottom comprising a blank cut, scored and folded to form foldably connected side walls and a closure wall, a detachable connection between said closure wall and the opposite

side wall for securing said closure wall in closed position, top closure flaps on said walls, a pair of opposite side walls having bottom closure flaps foldably connected therewith and each formed with a fold line and adapted to fold inwardly at said fold line between the side walls when said side walls are collapsed, and a bottom closure flap foldably connected with the intermediate side wall and having a glued connection with one of said inwardly folding flaps, the other of said inwardly folding flaps having a flange extending foldably inwardly between the side walls and detachably glued to said closure wall, said bottom closure flaps being moved to erected position normal to said side walls by erecting movement of said side walls and said closure wall being detachable from said side wall and from said flange and movable to open position to expose the carton contents with the carton in erected condition.

2. A collapsible carton having a self-erecting bottom comprising a blank cut, scored and folded to form foldably connected side walls and a closure wall, a securing strip on said closure wall detachably connected with the free edge of the opposite side wall, top closure flaps on said walls, a pair of opposite side walls having bottom closure flaps foldably connected therewith and each provided with a fold line and adapted to fold inwardly at said line between the side walls when said side walls are collapsed, and a bottom closure flap foldably connected with the intermediate side wall and having a glued connection with one of said inwardly folding flaps, the other of said inwardly folding flaps having a flange extending foldably inwardly between the side walls and detachably glued to said closure wall, said bottom closure flaps being moved to erected position normal to said side walls by erecting movement of said side walls, and said securing strip and closure wall being detachable from said side wall and from said flange and movable to open position with the carton in erected condition, said free edge of said side wall having an inwardly extending slit adjacent one end thereof, and said closure wall after opening being movable again to closed position with the major portion of said securing strip inserted inside said free edge and an end portion extending outwardly through said slit and separated from contact with the carton contents for grasping to move said closure wall without soiling the fingers.

3. A collapsible carton having a self-erecting bottom comprising a one-piece blank cut, scored and folded to form foldably connected front, rear, side and closure walls, a detachable connection between said closure wall and said front wall, top closure flaps on said walls, said front and rear walls having bottom closure flaps foldably connected therewith and each formed with a fold line and adapted to fold inwardly at said fold line between the side walls when said side walls are collapsed, and an inner bottom closure flap on said side wall having substantially the size and shape of the inside bottom of said carton and adapted to cover the same, said inner bottom flap having a glued connection with one of said inwardly folding flaps, the other of said inwardly folding flaps having a flange extending foldably inwardly between said front and rear walls and detachably glued to said closure wall, said bottom closure flaps being moved to erected position normal to said side walls by erecting movement of said walls, and said closure wall being detachable from said side wall and from said flange and movable to open position to expose the carton contents with the carton in erected condition.

4. A collapsible carton having a self-erecting bottom comprising a one-piece blank cut, scored and folded to form foldably connected front, rear, side and closure walls, a securing strip on said closure wall detachably glued to the free edge of said front wall and having a free pull tab, top closure flaps on said walls, bottom closure flaps on said front and rear walls and each provided with a fold line and adapted to fold inwardly at said line between said walls when said walls are collapsed, an inner

bottom closure flap on said side wall having substantially the size and shape of the inside bottom of the carton to cover the same and having a glued connection with one of said inwardly folding flaps, and a flange on the other of said inwardly folding flaps extending foldably inwardly between said front and rear walls and detachably glued to said closure wall, said bottom flaps being moved to erected position normal to said walls by erecting movement of said walls, said inwardly folding flaps having notched edges for engagement with each other to locate the same in erected position, and said securing strip and closure wall being detachable from said side wall and from said flange and movable to open position to expose the carton contents with the carton in erected condition.

5. A collapsible carton having a self-erecting bottom comprising a one-piece blank cut, scored and folded to form foldably connected front, rear, side and closure walls, a detachable connection between said closure wall and said front wall, top closure flaps on said walls, a pair of bottom closure flaps foldably connected with said front and rear walls and each formed with a fold line and adapted to fold inwardly at said line between said walls when said walls are collapsed, an inner bottom closure flap foldably connected with said side wall and having a glued connection with one of said inwardly folding flaps, said bottom closure flaps being moved to erected position normal to said walls by erecting movement of said walls, said closure wall being formed with a transverse portion separable from the remainder of said closure wall, said transverse portion having a glued connection with the other of said inwardly folding flaps and extending upwardly from the bottom of said carton, the remainder of said closure wall being detachable from said front wall and from said transverse portion and movable to open position with said transverse portion connecting said front and rear walls for maintaining the same in erected position.

6. A collapsible carton having a self-erecting bottom comprising a blank cut, scored and folded to form foldably connected side walls and a closure wall, a detachable connection between said closure wall and the free edge of one of said side walls, top closure flaps on said walls, a pair of opposite side walls having bottom closure flaps foldably connected therewith and each formed with a fold line and adapted to fold inwardly at said fold line between the side walls when said side walls are collapsed, and a bottom closure flap foldably connected with the intermediate side wall and having a glued connection with one of said inwardly folding flaps, the other of said inwardly folding flaps having a flange extending foldably inwardly between the side walls and detachably glued to said closure wall, said closure wall being partially cut through along the edge of the area of contact with said flange for providing a weakened surface area for attachment to said flange, said bottom closure flaps being moved to erected position normal to said side and closure walls by erecting movement of said walls, and said closure wall being detachable from said side wall and flange and movable to open position with a portion of said weakened area of said closure wall connected with said flange to maintain the connection between said opposite side walls and maintain said carton in erected condition.

7. A collapsible carton having a self-erecting bottom comprising a one-piece blank cut, scored and folded to form foldably connected side walls and a closure wall, a securing strip on said closure wall detachably connected with the free edge of one of said side walls, top closure flaps on said walls, bottom closure flaps foldably connected with oppositely arranged side walls and each formed with a fold line and adapted to fold inwardly at said line between the side walls when said side walls are collapsed and a bottom closure flap foldably connected with the intermediate side wall and having a glued connection with one of said inwardly folding flaps, the

other of said inwardly folding flaps having a flange extending foldably inwardly between the side walls and detachably glued to said closure wall, said closure wall being partially cut through along the edge of the area of contact with said flange for providing a weakened surface area for attachment to said flange, said bottom closure flaps being moved to erected position normal to said side walls by erecting movement of said side walls, and said securing strip and closure wall being detachable from said side wall and said flange and movable to open position with a portion of said weakened area of said closure wall connected with said flange to maintain the connection between said opposite side walls and maintain said carton in erected condition, said free edge of said side wall having an inwardly extending slit adjacent one end thereof and said closure wall after opening being movable again to closed position with the major portion of said securing strip inserted inside said free edge and an end portion extending outwardly through said slit and protected against contact with the carton contents.

8. A collapsible carton having a self-erecting bottom comprising a one-piece blank cut, scored and folded to form foldably connected front, rear, side and closure walls, a securing strip on said closure wall detachably glued to the free edge of said front wall and having a free pull tab, top closure flaps on said walls, a pair of bottom closure flaps foldably connected with said front and rear walls and each formed with a fold line and adapted to fold inwardly at said line between said walls when said walls are collapsed, and an inner bottom closure flap foldably connected with said side wall and having a glued connection with said inwardly folding flap on said rear wall, the other of said inwardly folding flaps having a flange extending foldably inwardly between said walls and detachably glued to said closure wall, said closure wall being partially cut through along the edge of the area of contact with said flange for providing a weakened surface area for attachment to said flange, said bottom closure flaps being moved to erected position normal to said side walls by erecting movement of said side walls and said securing strip and closure wall being detachable from said front wall and flange and movable to open position with a portion of said weakened area of said closure wall connected with said flange to maintain the connection between said front and rear walls and maintain said carton in erected condition.

9. A collapsible carton having a self-erecting bottom comprising a one-piece blank cut, scored and folded to form foldably connected front, rear, side and closure walls, a detachable connection between said closure wall and the free edge of said front wall, top closure flaps on said walls, a pair of bottom closure flaps foldably connected with said front and rear walls and each formed with a fold line and adapted to fold inwardly at said fold line between the side walls when said walls are collapsed, and an inner bottom closure flap on said side wall having substantially the size and shape of the inside of the bottom of said carton and adapted to cover the same, said inner bottom flap having a glued connection with the inwardly folding flap of said rear wall, the other of said inwardly folding flaps having a flange extending foldably inwardly between the side walls and detachably glued to said closure wall, said closure wall being partially cut through along the edge of the area of contact with said flange for providing a weakened surface area for attachment to said flange, said bottom closure flaps being moved to erected position normal to said walls by erecting movement of said walls, and said closure wall being detachable from said front wall and said flange and movable to open position with a portion of said weakened area of said closure wall connected with said flange to maintain the connection between said front and rear walls and maintain said carton in erected condition.

10. A collapsible carton having a self-erecting bottom comprising a one-piece blank cut, scored and folded to form foldably connected front, rear, side and closure walls, a securing strip on said closure wall detachably connected with the free edge of said front wall and provided with a free pull tab for detaching the same, top closure flaps on said walls, a pair of bottom closure flaps foldably connected with said front and rear walls and each provided with a fold line and adapted to fold inwardly at said line between said walls when said walls are collapsed, an inner bottom closure flap foldably connected with said side wall and having a glued connection with said rear wall, one of said inwardly folding flaps having a flange extending foldably inwardly between said walls and detachably glued to said closure wall, said closure wall being partially cut through along the edge of the area of contact with said flange for providing a weakened surface area for attachment to said flange, said bottom closure flaps being moved to erected position normal to said walls by erecting movement thereof, said inwardly folding flaps having notched edges for engagement with each other to secure the same in erected position, and said securing strip and closure wall being detachable from said front wall and flange and movable to open position with a portion of said weakened area of said closure wall connected with said flange to maintain the connection between said front and rear walls and maintain said carton in erected condition.
11. A collapsible carton having a self-erecting bottom, comprising a blank cut, scored and folded to form foldably connected front, rear and side walls and a closure wall foldably hinged to said rear wall, a detachable connection between said closure wall and said front wall, top closure flaps on said walls, a pair of bottom closure flaps foldably connected with said front and rear walls and each formed with a fold line and adapted to fold inwardly at said fold line between side walls when said side walls are collapsed, an inner bottom closure flap foldably connected with said side wall and having a glued connection with one of said inwardly folded flaps, and a flange on the other of said inwardly folding flaps extending foldably inwardly between the front and rear walls and detachably glued to said closure wall with one end thereof extended and glued to said rear wall, said bottom closure flaps being moved to erected position normal to said walls by erecting movement thereof and said closure wall being detachable from said front wall and from said flange and movable to open position to expose the carton contents with the carton in erected position.

12. A collapsible carton having a self-erecting bottom comprising a one-piece blank cut, scored and folded to form front, rear and side walls and a closure wall foldably hinged to the top of said rear wall, a detachable connection between said closure wall and said front wall, top closure flaps on said walls, a pair of bottom closure flaps foldably connected with said front and rear walls and each formed with a fold line and adapted to fold inwardly at said line between said walls when said walls are collapsed, an inner bottom closure flap foldably connected with said side wall and having a glued connection with the inwardly folding flap of said rear wall, and a flange on the other of said inwardly folding flaps extending foldably inwardly between said walls and detachably glued to said closure wall with one end extended and glued to said rear wall, said bottom closure flaps being moved to erected position normal to said walls by erecting movement thereof, and said closure wall being detachable from said front wall and from said flange and movable to open position to expose the carton contents with the carton in erected condition.
